CONTROL SYSTEM

James W. Cooke, Schenectady, N. Y., assignor to
 General Electric Company, a corporation of
 New York

Application January 14, 1942, Serial No. 426,735

14 Claims. (CL 172—152)

This invention relates to control systems, more particularly to systems for controlling the operation of electric motors, and it has for an object the provision of a simple, reliable, and improved control system of this character.

More specifically, the invention relates to motor control systems in which the motor is subjected to overhauling loads and in which a power type limit switch is employed to interrupt the power circuits of the motor. A crane hoist is a good example of an installation of this character. In a crane hoist, the hoist is usually driven by a series direct current motor, and a power type limit switch is provided for interrupting the power circuits of the motor at the overhoist limit and for establishing a loop dynamic braking circuit in which a dynamic braking resistor is included when the switch is tripped from one position to another by the crane hook block as it approaches its upper limit of travel. The dynamic braking circuit which is thus established assists the solenoid brake in bringing the hook to a quick stop even though the crane operator runs the hook into the limit switch zone with the master switch on the full speed point hoist and with no load on the hook.

The limit switch accomplishes satisfactorily the purpose for which it is primarily intended, i. e. disconnecting the motor from its power supply and bringing it rapidly to a stop when the hook block reaches its upper limit. It does, however, result in certain objectionable operating characteristics when the hook is being lowered out of the limit switch zone at the time the motor is first energized for lowering until the limit switch is reset to its normal position as the hook reaches the limit end of the switch zone in the lowering direction.

In normal operation, crane hoist controllers used with direct current series motors provide for connecting the motor as a series machine in the hoist direction and as the equivalent of a shunt machine in the lowering direction. The shunt circuit employed for lowering develops either a motoring torque for driving down an empty hook or a dynamic braking torque for retarding an overhauling load. The change from one torque to the other is inherent in the system itself.

However, within the limit switch zone, the contacts of the power type limit switch so change the connections between the motor armature and series field winding that a straight series circuit with the armature and field winding shunted by the dynamic braking resistance of the

loop circuit is established in the lowering direction as long as the limit switch is tripped, i. e. while the hook block remains in the limit switch zone.

5 When both the armature and field winding of a series motor are shunted, only series operating characteristics are produced and no dynamic braking torque is available to retard the speed of an overhauling load. Since the pull of the load and the torque of the motor are in the same direction, the hook block and motor can attain an excessively high speed in coming out of the limit switch zone between the time that the motor is first connected to the power supply and the time that the limit switch resets.

Furthermore, the light hook hoisting speeds of modern cranes are being greatly increased. At the present time, light hook hoisting speeds of the order of 250 per cent of rated full load speed are quite common, and some cranes are being operated at speeds as high as 300 per cent of rated full load speed. These high speeds have made it necessary to increase the amount of dynamic braking resistance which is inserted in the loop dynamic braking circuit by the limit switch when the hook reaches the overhoist limit. Since this dynamic braking resistor is shunted around the motor armature and series field winding when the lowering connections are established by the master switch, a correspondingly increased amount of current is passed through the motor, a correspondingly increased motor torque is developed, and the speed of the motor in the lowering direction is correspondingly increased. When the descending load reaches the position at which the limit switch resets, the equivalent of a shunt motor connection is established. Consequently, if the motor has attained a relatively high speed, e. g. 250 per cent of rated full load speed, or higher, in coming out of the limit switch zone, its speed will suddenly be reduced when the limit switch is reset. This sudden change in speed subjects all the mechanical parts of the crane to a severe shock which is highly objectionable.

Accordingly, an additional object of this invention is the provision of means for limiting the speed of the motor to a safe value while lowering out of the limit zone.

50 The hoist motor, brake, contacts of the power type limit switch, and the loop dynamic braking resistor controlled by the limit switch are located on the trolley motion of the crane. The balance of the equipment such as contactors, relays, switches, and speed controlling resistors,

are mounted on a panel which is located on the bridge structure of the crane. Consequently, trolley wires and cooperating collector shoes are required to transfer power between the control apparatus panel on the bridge and the motor, solenoid brake, and limit switch on the trolley motion structure. It is desirable that the number of trolley wires be kept at a minimum. It is also desirable from the point of view of maintenance and reliability to mount as much of the electrical equipment as possible on the panel which is located on the bridge where it is better protected and more accessible for inspection and repair than would be the case if it were mounted on the trolley motion structure.

Another object of the invention, therefore, is the provision of means for limiting the speed while lowering out of the limit zone, which can be mounted on the control panel and which is connected in such a manner that the number of trolley wires required is kept at a minimum.

In carrying the invention into effect in one form thereof, means controlled by operation of the limit switch and responsive to a terminal electrical operating condition of the motor following operation of the limit switch are mounted on the control panel and serve to establish a dynamic braking circuit for the motor while the motor is lowering out of the limit zone and automatically to interrupt this dynamic braking circuit as a result of the resetting of the limit switch as the hoist lowers out of the limit switch zone.

Another aspect of this invention is the provision of means for preventing oscillation of the hook in the overhoist limit zone. Heretofore crane hoist controls have been provided with a spring closed contactor for establishing an emergency dynamic braking circuit in shunt with the motor armature and field winding to provide slow speed lowering in the event of power failure or failure of the solenoid brake to set. In order to obtain improved speed regulation, it has been customary to maintain this emergency dynamic braking contactor closed on one or more low speed points of the master switch. This shunted motor connection introduces an undesirable operating condition in that it establishes a by-pass or sneak circuit around the motor armature and series field winding which keeps the series brake released even though the limit switch has operated to disconnect the hoist motor from its source. Consequently, if the load is overhauling, it will descend beyond the point at which the limit switch resets itself and will then start up again. Thus, an oscillating condition of the crane hook is set up which will continue until the operator returns the master switch to the off position in which the brake can set and stop the hoist. This condition is, of course, very undesirable because it is extremely disconcerting to an operator to observe that the load is being lowered although the master switch is in a hoisting position, and also because with heavy loads this oscillation produces high and unnecessary strains in the apparatus.

Heretofore, additional apparatus has been required to correct this condition. The present invention safely limits the speed of the motor while lowering out of the limit zone and also makes it possible to obtain during normal operation the improved speed regulation which is desired without maintaining the emergency dynamic braking contactor closed on any of the hoist positions and thereby eliminates the necessity of the addition-

al apparatus that formerly was required to prevent oscillation of the hook in the limit zone.

Furthermore, this invention provides greatly improved speed regulation on the low speed hoist positions of the master switch. In addition, it provides dynamic braking of the hook in the low speed hoisting positions of the master switch and thereby eliminates coasting of an empty or lightly loaded hook in the hoisting direction after the master switch has been notched back from a high speed position to a low speed position.

For a better and more complete understanding of the invention, reference should now be had to the following specification and to the accompanying drawings in which Fig. 1 is a simple, diagrammatical illustration of the master switch and control circuits controlled thereby; Fig. 2 is a simple, diagrammatical sketch of the power circuits and of the contacts therein controlled by the master switch and control circuits of Fig. 1; and Fig. 3 is a simple, diagrammatical sketch of a crane hoist cable and power type limit switch operated thereby.

Referring now to the drawings, the hook 10 of a crane hoist is connected to a cable 11 which is wound upon a drum 12. The hoist cable drum is driven by suitable driving means such as the electric motor 13. This hoist motor is illustrated as a series type direct current motor having a series field winding 13a and a commutating field winding 13b. The motor may be supplied from any suitable source such as represented by the two supply lines 14 and 15. A pair of reversing contactors 16 and 17 is provided for connecting the hoist motor to the power supply for rotation in either the hoisting or lowering direction. These contactors have operating coils 16a and 17a, respectively, as indicated in Fig. 2. The operating coils 16a and 17a are shown included in their controlling circuits in Fig. 1. When contactor 16 is closed, the motor 13 is connected to the source 14, 15 for rotation in the hoisting direction, and when contactor 17 is closed, the motor is connected to the source for rotation in the lowering direction.

Referring to Fig. 1, the operating coils 16a and 17a of the directional contactors are under the control of a multiposition, reversing type master switch 18. The master switch 18 is illustrated as having five "hoist" positions and five "lower" positions. A larger or smaller number of operating positions for each direction of rotation may be provided if desired.

The hoist motor 13 is provided with a solenoid brake (not shown) having its operating solenoid 19 connected in series with the motor series field winding 13a through resistors 20, 21, 22, and 23. The brake is normally set by a spring and is released by the solenoid 19 when the solenoid is energized. Resistors 20, 21 and 22 are active during the lowering operation, but are short circuited in all positions of the master switch during the hoisting operation.

A normally spring closed contactor 24 serves to establish a shunting connection for the armature and field winding of motor 13 through a resistor 25 in the first or lowest speed position of the master switch in the lowering direction for the purpose of providing a desired slow lowering speed. This contactor is also closed in the off position of the master switch. As shown, contactor 24 is provided with an operating coil 24a which when energized serves to open the contactor against the tension of its closing spring.

(not shown). The control circuit for the operating coil 24a is shown in Fig. 1.

A plurality of accelerating resistors 26 and 27 are connected in series with the armature of motor 13. These resistors are controlled by means of accelerating contractors 28 and 29 having operating coils 28a and 29a, respectively. The control circuit for the operating coils 28a and 29a are shown in Fig. 1.

A power type overhoist limit switch 30 is provided for disconnecting the motor 13 from its power supply at a predetermined position of the hook block in order to prevent overtravel in the hoisting direction. This limit switch is illustrated in Fig. 3 as comprising a plurality of pairs of stationary contacts 31, 32, 33 and 34 and a movable arm 30a carrying a plurality of pairs of movable contacts which cooperate with the stationary contacts. A projecting member 35 secured to the cable 11 serves to actuate the movable contact carrying member 30a. The contacts 31 and 32 are normally closed and the contacts 33 and 34 are normally open except when the hook block reaches its overhoist limit and the member 35 actuates the movable member 30a to open contacts 31 and 32 and to close contacts 33 and 34. The hoist motor 13, solenoid brake 19, and limit switch 30 are mounted on the trolley motion structure, and the various resistors and contactors described in the foregoing are mounted on a main magnetic control panel which is usually located on the bridge structure. The master switch 18 is of course also mounted on the bridge structure. Thus it becomes necessary to make the power connections between the motor and brake and the panel by means of trolley wires and collector shoes. These trolley wires and collector shoes are indicated by reference characters 36, 37, 38 and 39 in Fig. 2.

For the purpose of limiting the speed of the motor when lowering out of the limit switch zone after the limit switch has been tripped, means comprising a control relay 40, a contactor 41, and a dynamic braking resistor 43 are provided. These parts are preferably mounted on the control panel on the bridge structure where they are accessible for inspection and repair. When the contacts of contactor 41 are closed, the dynamic braking resistor 43 is connected in a shunt circuit to the armature terminals 13c and 13d of the hoist motor 13. As shown in Fig. 2, one terminal of the dynamic braking resistor 43 is connected through conductor 44, trolley 36 to the armature terminal 13c, and the other terminal of resistor 43 is connected through the contacts of contactor 41 to the opposite armature terminal 13d. One additional trolley wire 45 is required to complete the connections between the resistor 43 through contacts of contactor 41 to the armature terminal 13d. The operating coil of relay 40 is connected from the conductor 44 to the conductor 46. The conductors 44 and 46 are on the control panel on the bridge. It will be observed in Fig. 2, that conductor 44 leads through trolley 36 and limit switch contact 32 to one terminal of the series field winding 13a and that the conductor 46 leads through trolley 37 to the opposite terminal of the series field winding 13a. Consequently, when the limit switch contact 32 is closed, the operating coil 40a of relay 40 is connected across the series field winding 13a. The relay 40 is provided with two pairs of normally open contacts 40b and 40c and as shown in Fig. 1, the normally open con-

tacts 40c are connected in series with the normally closed interlock contacts 16b of the hoist contactor and the operating coil 41a of the dynamic braking contactor 41. The relay 40 is so designed that the voltage drop across the field winding 13a is insufficient to pick up relay 40. Therefore when the operating coil 40a of relay 40 is connected across the field winding 13a, its contacts are open. Since the operating coil 41a of contactor 41 is connected in series with the normally open contacts 40c of relay 40, the contactor 41 cannot be picked up when the operating coil 40a of relay 40 is connected across field winding 13a except in the first two positions hoist of the master switch. In these positions, the contactor 41 is picked up directly by a circuit completed through the master switch.

With the foregoing understanding of the elements and their organization in the control system, the operation of the system itself will readily be understood from the following detailed description.

It is assumed that the hook is in its lower position and that the master switch 18 is in its central or "off" position. The apparatus is all in the normal position in which it is illustrated in the drawings, and the hoist motor 13 is at standstill and the solenoid brake 19 set by its operating spring. In the off position of the master switch 18 an emergency dynamic braking circuit is established which is traced from the armature terminal 13d through limit switch contact 31, dynamic braking resistor 25, normally closed contacts of emergency dynamic braking contactor 24, series field winding 13a, limit switch contact 32 to terminal 13c of the motor. Also, in the off position of the master switch, the operating coils 41a, 48a, and 49a of contactors 41, 48 and 49, respectively, are energized. The energizing circuits for operating coils 41a, 48a, and 49a are traced in Fig. 1 from the side 50 of a suitable source of control voltage through conductor 51, fingers 18i, 18j, and 18k, of master switch 18, bridged by cooperating segments and operating coils 41a, 48a, and 49a in parallel to the opposite side 52 of the source of control voltage. In this connection, it will be noted that the operating coil 48a of contactor 48 is energized and that the energizing circuit for coil 41a is completed when the contacts 48b of contactor 48 close.

As a result, contactors 41, 48, and 49 are closed and resistors 20, 21, and 22 are short circuited.

To hoist the hook and its load, the master switch is operated to its first position "hoist." In this position, the coil 54a of line contactor 54 is energized. The circuit is traced from the side 50 of the source of control voltage to power conductor 51, fingers 18a of the master switch bridged by the cooperating segment on the hoist side of the master switch, conductor 55, coil 54a to the opposite side 52 of the control voltage source. Contactor 54 closes its contacts 54b in response to energization and connects one terminal of the hoist motor to the side 15 of the power supply.

Simultaneously, the operating coil 16a of hoist contactor 16 is energized. The circuit for this coil is traced from power conductor 51 through fingers 18e of the master switch bridged by the cooperating segment, normally closed contacts 56b of a control contactor 56, operating coil 16a of the hoist contactor to the side 52 of the source. As a result, the hoist contactor closes its normally open contacts 16b, 16c, and 16d, and opens its

normally closed contact 16e. Contacts 16b in closing complete the power circuit for the motor which is traced from the side 14 of the supply source through conductor 51, contacts 16b of the hoist contactor, accelerating resistors 21 and 26, limit switch contacts 31, armature of motor 13, conductor 58, limit switch contacts 32, series field winding 13a, series brake operating solenoid 19, contacts 41b of contactor 41, conductor 59, resistor 23, contacts 54b of contactor 54 to the side 15 of the power supply. Contacts 16c of the hoist contactor in closing complete an energizing circuit for the operating coil 28a of the emergency dynamic braking contactor. This energizing circuit is traced from the power conductor 51 through fingers 18g of the master switch bridged by the cooperating segment on the hoist side of the master switch, conductor 60, contacts 16c of the hoist contactor, and through operating coil 28a to the side 52 of the control voltage source. In response to energization, contactor 24 opens its normally closed contacts 24b to interrupt the emergency dynamic braking circuit.

Also on the first point hoist of the master switch, an energizing circuit is completed for the operating coil 41a of contactor 41 which is traced from the power conductor 51 through fingers of the master switch 18b bridged by the cooperating segment of the master switch, and through operating coil 41a to the side 52 of the source. Contactor 41 closes its contacts 41b to complete a shunt circuit for the armature of motor 13 through resistor 43. As a result of this armature shunting circuit, the motor 13 rotates at a very stable, slow speed and hoists the load. It will be observed that the operating coil 41a of contactor 41 remains energized on the second point hoist of the master switch, and consequently the armature shunting circuit through resistor 43 remains intact on the second position hoist. It will thus be clear, that if the motor is operating on one of the higher speed points hoist of the master switch, e. g. the fifth point, and the master switch is suddenly notched back to the second or first position to effect a lower hoisting speed, this armature shunting circuit through the resistor 43 is immediately established. This provides a very effective dynamic braking circuit which rapidly reduces the speed of the motor to the low speed corresponding to the speed point to which the master switch is returned. Consequently, the motor is prevented from coasting for a period at high speed which it would otherwise do in the case of an empty or lightly loaded hook.

To increase the speed, the master switch 18 is moved to its second position hoist. In this position, a circuit is completed for the operating coil 61a of accelerating contactor 61. This circuit is traced from the power conductor 51, through fingers 18h bridged by cooperating segments on the hoist side of the master switch, conductors 62 and 63, contacts 16d of the hoist contactor and through operating coil 61a to the side 52 of the source. In response to energization, contactor 61 closes its contacts 61b to short circuit accelerating resistor 23. This results in increasing the speed of motor 13.

In the third position hoist of the master switch, the energizing circuit for operating coil 41a is interrupted at the fingers 18b. As a result of its deenergization, contactor 41 opens its contacts 41b to interrupt the armature shunting circuit through the resistor 43. This results in further increasing the speed of the motor 13.

Movement of the master switch to the fourth position hoist completes an energizing circuit for the operating coil 28a of contactor 28. This circuit is traced from the power conductor 51 through fingers 18l of the master switch bridged by the cooperating segment on the hoist side, conductor 64, normally closed contacts 65b, operating coil 28a of contactor 28 to the side 52 of the source. Relay 65 is preferably a time delay relay which closes its contacts a predetermined interval of time after the deenergization of its operating coil 65a by the opening of contacts 61c of contactor 61. Therefore the energizing circuit for the operating coil 28a is completed at the expiration of this predetermined interval of time and the contactor closes its contacts 28b to short circuit resistor section 26 and further increase the speed of the motor. Contactor 28 also closes its contacts 28c to prepare the energizing circuit for the operating coil 29a of accelerating contactor 29.

Movement of the master switch 18 to the fifth position hoist completes the energizing circuit for the operating coil 29a and contactor 29 closes its contacts 29b to short circuit resistance section 27 and thereby accelerate motor 13 to its full speed.

As the hook block reaches the overhoist limit, the projection 35 strikes the movable contact carrying arm 30a and moves it from the position shown to a position in which the contacts 31 and 32 are open and contacts 33 and 34 are closed. Contacts 31 and 32 in opening disconnect the motor 13 from the source 14, 15 and contacts 33 and 34 in closing complete a dynamic braking circuit for the armature of motor 13 which is traced from the armature terminal 13d through contacts 33, series field winding 13a, dynamic braking resistor 65, contacts 34 and conductor 50 through the left-hand terminal 13c of the motor armature. As a result of the establishment of this dynamic braking circuit, a large braking torque is set up which is effective in rapidly reducing the speed of the motor. In this connection it will be noted that the contacts 33 and 34 of the limit switch reconnect the series field winding 13a to the motor armature so that the current flows through the series field winding in the same direction as it did during the previous power operation. As a result, the current in the series field winding does not decrease to zero, and the braking torque is therefore maintained at maximum value. Since the operating coil 24a of the emergency dynamic braking contactor 24 is maintained energized in all the hoist positions of the master switch, the opening of limit switch contacts 31 and 32 therefore interrupts the energization of the solenoid 19 of the solenoid brake and as a result, the spring of the brake sets the shoes against the drum and assists the dynamic braking torque of the motor in bringing the motor to rest.

Since the mechanical brake is set, the load will not descend, and consequently the undesirable oscillating condition described in the foregoing is completely corrected. Consequently, the special apparatus which was required to correct this condition in crane hoist controls used heretofore is entirely eliminated.

The opening of limit switch contacts 32 disconnects the left-hand terminal of the series field winding 13a from the motor armature terminal 13c. Consequently, the operating coil 40a of relay 40 is no longer connected across the series field winding 13a but on the contrary, is

connected across the armature and series field winding. The voltage drop across the armature and series field winding is sufficient to energize the operating coil 40a and consequently, the relay 40 picks up and closes its contacts 40b and 40c. Contacts 40c in closing prepare an energizing circuit for the operating coil 41a of dynamic braking contactor 41 which is interrupted, however, at the interlock contacts 16c of the hoist contactor.

To lower the hoist out of the limit switch zone, the master switch must be moved to one of its lowering positions. The return of the master switch to the off position restores the apparatus to the normal position shown in the drawings with the exception of the limit switch which remains in the tripped position.

Movement of the master switch to the first position lowering completes an energizing circuit for the operating coil 54a of contactor 54 which closes its contacts 54b to connect the junction point of the field winding 13a and dynamic braking resistor 65 to the side 15 of the power supply. The contactor 47, 48, and 49 remain picked up in the first position lowering. The energizing circuits for the operating coils 47a, 48a, and 49a of these contactors are the same as traced for the hoisting operation. Consequently, resistors 20, 21 and 22 are short circuited on the first position lowering. In response to the voltage drop across the armature of the motor 13 and the series field winding 13a, the relay 40 is energized and closes its contacts 40b and 40c. Also in the first position lowering of the master switch, the operating coil 17a of the lowering contactor is energized and the lowering contactor closes its normally open contacts 17b and 17c. Contacts 17b in closing complete connections from the motor armature to the side 14 of the power supply. The motor circuit is traced from the side 14 of the power supply through the line switch in the closed position thereof, contacts 17b of lowering contactor, trolley 36 and conductor 58 through commutating field winding 13b and armature of motor 13, limit switch contacts 33, conductor 66, series field winding 13a, brake solenoid 19, contacts 47b, conductor 59, and resistor 23 to the side 15 of the power supply. The operating coil 56a of the contactor 56 is also energized on the first position lowering of the master switch and the contactor closes its contacts 56b. However, this has very little effect on the operation of the motor at this point since the limit switch contacts 31 are still open.

On the second position lowering of the master switch, an energizing circuit is established for the operating coil 24a of emergency dynamic braking contactor 24, and in response to its energization, the contactor opens its contacts 24b. This, however, has substantially no effect on the speed of the motor when operating in the limit zone. As the master switch leaves its second position lowering, the energizing circuits for the relay 53 and contactor 47 are interrupted. In response to deenergization, relay 53 opens its normally open contacts 53a and contactor 47 opens its normally open contacts 47b, thereby to insert resistance section 20 in the motor circuit. Contactor 47 in dropping out also closes its normally closed contacts 47c to prepare an energizing circuit for the operating coil 61a of contactor 61.

Between the third and fourth positions lowering of the master switch, the fingers 18h are bridged by the cooperating segments on the low-

ering side of the master switch further to prepare the energizing circuit for the operating coil 61a of contactor 61. However, this energizing circuit remains open at interlock contacts 48d of contactor 48.

Movement of the master switch to the fourth position lowering interrupts the connections of the operating coil 48a of contactor 48 through the fingers 18j of the master switch. However, the operating coil 48a remains energized through the contacts 40b of relay 40. Consequently, movement of the master switch to the fourth and fifth positions lowering will have no further effect on the control as long as the relay 40 remains energized. Since the relay 40 will remain energized as long as the hook block is in the limit zone, movement of the master switch to the fourth and fifth positions lowering will have no effect on the control as long as the hook block remains in the limit zone.

When the master switch was moved to the first position lowering, the motor 13 was connected to the source with the armature in series with the field winding 13a. Although the loop circuit through the armature, field winding 13a, resistor 65 and limit switch contacts 33 and 34 provided a dynamic braking circuit when the motor was disconnected from the power supply by the tripping of the limit switch, dynamic braking of the motor is no longer available when the motor is reconnected to the power supply by the lowering contactor 17 because the motor armature and series field winding are connected in series to the source with the resistor 65 connected in parallel with the armature and field winding. Consequently, the only effect of the resistor 65 is to divert a portion of the current from the power supply from the armature and field winding. As a result of this loss of dynamic braking, the motoring torque and the overhauling torque produced by the load on the hook are in the same direction. In the absence of any means to prevent it, it is possible for the motor 13 to attain an excessively high speed in the lowering direction before the hook block reaches the limit and resets the limit switch 30. This is prevented, however, by the action of the relay 40, and the contactor 41 in conjunction with the normally closed interlocks of the hoisting contactor. When relay 40 in responding to the voltage across the armature and field winding 13a of the motor closed its contacts 40c, it completed an energizing circuit for the operating coil 41a of contactor 41. This circuit is traced from the power conductor 51 through fingers 18a of the master switch bridged by the cooperating segment on the lowering side, conductor 61, contacts 40c of relay 40, conductor 68, normally closed interlock contacts 16e of hoist contactor 16, and thence through operating coil 41a of contactor 41 to the side 52 of the source. Contactor 41 in responding to energization closed its contacts 41b to complete a dynamic braking circuit through the resistor 43 in parallel with the armature of the motor 13. The shunting of the armature of the motor 13 by the resistor 43 causes the motor to have shunt motor characteristics so that either motor torque or dynamic braking torque, within limits, is obtained depending upon the load conditions. If the load is overhauling, dynamic braking torque will be obtained and the descending speed of the motor in the limit zone will be limited to a reasonable value.

Since the speed of the motor 13 is maintained at a reasonable value during the descent of the

hook block through the limit zone, no severe shocks or strains are imposed upon the apparatus as a result of a large and sudden decrease in speed when the limit switch resets.

When the hook block reaches the reset point of the limit in the lowering direction, the member 35 engages the contact carrying arm 30a of the limit switch, thereby resetting the limit switch to open the contacts 33 and 34 and close the contacts 31 and 32. Contacts 33 and 34 in opening interrupt the loop circuit through the armature of motor 13, the series field winding and resistor 65. Contact 32, in closing, connects the field winding 13a across the source 15 through resistor 20 and contact 31 in closing connects the armature of the motor to the source through resistors 26 and 27. The motor is now connected as a shunt motor with the current through the field winding 13a limited by the resistor 20.

The closing of contact 32 also connects the operating coil 40a of relay 40 directly across the field winding 13a. As previously pointed out, the voltage drop across the field winding 13a does not energize the operating coil 40a sufficiently to maintain the relay picked up. Consequently, the relay drops out and opens its contacts 40b and 40c. Contacts 40c in opening interrupt the energizing circuit for the operating coil 41a of contactor 41. This contactor in response to deenergization opens its contacts 41b to interrupt the armature shunt circuit through the resistor 43, thereby removing the dynamic braking effect of this circuit.

As explained in the foregoing, the progressive operation of the accelerating contactors was interrupted by the closing of the contacts 40b of the relay 40 so that even though the master switch were advanced to the fifth position lowering, the effect on the control was the same as if the master switch had not been advanced beyond the third position lowering. The opening of contacts 40b therefore permits the control to resume its progressive operation to the point called for by the operating position of the master switch. Assuming that the master switch has been advanced to the fifth position lowering, the opening of contact 40b of relay 40 interrupts the energizing circuit for the operating coil 48a of contactor 48. In response to deenergization, contactor 48 opens its contacts 48b to insert resistor 21 in circuit with the field winding 13a, thereby weakening the field of the motor and increasing its speed. In the dropped out position of contactor 48, the normally closed contacts 48d complete the previously prepared energizing circuit for contactor 61. In response to energization contactor 61 closes its contacts 61b to short circuit the resistor 23, thereby increasing the speed of the motor, and also opens its contacts 61c to interrupt the energizing circuit for the operating coil 65a of time delay relay 65. This relay in responding to deenergization closes its contact 65a after a predetermined interval of time to complete an energizing circuit for the operating coil 28a of contactor 28. In response to energization, contactor 28 closes its contacts 28b to short circuit the resistor 26 in the armature circuit and thereby further increase the speed of the motor.

Simultaneously, contactor 28 closes its contacts 28c to complete an energizing circuit for the operating coil 29a of contactor 29. Responsively to energization, contactor 29 closes its contacts 29b to short circuit resistor 27, thereby further to increase the speed of the motor. In picking up, contactor 29 opens its normally closed

contacts 29c to interrupt the energizing circuit for the operating coil 49a of contactor 49. This contactor then drops out and opens its contacts 49b to insert the resistor 22 in the field circuit of the motor, thereby to weaken the field and to increase the speed of the motor to full speed.

Although in accordance with the provisions of the patent statutes this invention is described as embodied in concrete form and the principle thereof has been explained and the best mode in which it is now contemplated applying that principle, it will be understood that the apparatus shown and described is merely illustrative and that the invention is not limited thereto, since alterations and modifications will readily suggest themselves to persons skilled in the art without departing from the true spirit of this invention or from the scope of the annexed claims.

What I claim as new and desire to secure by Letters Patent of the United States is:

1. In combination, an electric motor having a series field winding, limit switch mechanism for disconnecting said motor from its source at a predetermined limit of operation and preparing

reverse power connections from said motor to said source, reversing switching means for completing said reverse power connections, and means responsive to an electrical operating condition of said motor upon completion of said reverse power connections for completing a dynamic braking circuit for said motor.

2. In combination, an electric motor having a series field winding, limit switch mechanism for disconnecting said motor from its source at a predetermined limit of operation, reversing switching means for completing reverse power connections from said motor to said source, means responsive to an electrical operating condition of said motor upon completion of said reverse power connections for completing a dynamic braking circuit for said motor, and means responsive to operation of said limit switch mechanism at said predetermined limit in the reverse direction of rotation of said motor for in-

terrupting said dynamic braking circuit.

3. In combination, an electric motor having a series field winding, limit switch mechanism for disconnecting said motor from its source at a predetermined limit of operation and means controlled by said limit switch and responsive to the voltage of said motor for completing a dynamic braking circuit for said motor and for interrupting said dynamic braking circuit at said limit of operation in the reverse direction of rotation of said motor.

4. A control system for hoists in which the hoist is driven by an electric motor having a series field winding comprising in combination, an electromagnetic switching device for controlling the continuity of a dynamic braking circuit for said motor and having an operating coil normally connected across said field winding, and overhoist limit switch mechanism for disconnecting said motor from its source at a predetermined limit of operation of said motor in one direction and connecting said operating coil across said motor to provide for completion of said dynamic braking circuit in response to the voltage across said motor and for deenergizing said coil at said limit of operation in the reverse direction of rotation of said motor thereby to interrupt said dynamic braking circuit.

5. In combination, an electric motor having a series field winding, limit switching mechanism actuated by said motor for disconnecting said

motor from its source at a predetermined limit of operation in one direction of rotation, reversing switching means for completing reverse power connections from said motor to said source, means responsive to the voltage across said motor following the disconnection of said motor from its source for completing a dynamic braking circuit for said motor, and responsive to operation of said limit switch at a predetermined limit in the reverse rotation of said motor for interrupting said dynamic braking circuit.

6. A control system for an electric motor having a series field winding comprising in combination, a dynamic braking resistor, limit switch mechanism for disconnecting said motor from its source at a predetermined limit of operation in one direction of rotation, and completing a series dynamic braking circuit through said resistor and said field winding and the armature of said motor, reversing switching means for completing reverse power connections from a point in the circuit between said armature and resistor to said source so that said motor is connected to said source with said dynamic braking resistor in parallel with said armature and series field winding, means responsive to the terminal voltage of said motor upon completion of said reverse power connections for completing a second dynamic braking circuit in parallel with the armature of said motor and responsive to operation of said limit switch at said predetermined limit in the reverse direction of rotation of said motor for interrupting said second dynamic braking circuit and completing power connections from said motor to said source with said field winding in a parallel circuit with said armature.

7. A control system for an electric motor having an armature and a series field winding comprising in combination, limit switch mechanism having normally closed contacts between a source and a first terminal of said armature and between the second terminal of said armature and a first terminal of said field winding and having normally open contacts between said first armature terminal and said first field terminal and between said second armature terminal and the second field terminal, said limit switch being actuated at a predetermined limit of operation of said motor to open said normally closed contacts and close said normally open contacts, a switching device having an operating coil connected from said second armature terminal to said second field terminal and contacts controlled by said coil for establishing a dynamic braking circuit in parallel with said armature following operation of said limit switch at said limit.

8. A control system for an electric motor having an armature and a series field winding comprising in combination, limit switch mechanism having normally closed contacts between a source and the line terminal of said armature and between the field terminal of said armature and the armature terminal of said field winding and having normally open contacts between the line terminal of said armature and the armature terminal of said field winding and between said field terminal of said armature and the remaining terminal of said field winding, a switching device having an operating coil connected between said field terminal of said armature and said remaining terminal of said field winding, said limit switch mechanism being actuated at a predetermined limit of operation of said motor to open said normally closed contacts thereby to disconnect the motor from its source and to connect said

coil across said armature and field winding and to close said normally open contacts to complete a first dynamic braking circuit through said armature and field winding, reversing switching means for connecting said armature to said source for reverse rotation with said dynamic braking circuit connected across said armature and field winding, and means responsive to the energization of said coil for completing a second dynamic braking circuit in parallel with said armature.

9. A control system for an electric motor having an armature and a series field winding comprising in combination, limit switch mechanism having normally closed contacts between a source and the line terminal of said armature and between the field terminal of said armature and the armature terminal of said field winding and having normally open contacts between the line terminal of said armature and the armature terminal of said field winding and between said field terminal of said armature and the remaining terminal of said field winding, a switching device having an operating coil connected between said field terminal of said armature and said remaining terminal of said field winding, a switching device having its operating coil connected between said field terminal of said armature and said remaining terminal of said field winding, said limit switch mechanism being actuated at a predetermined limit of operation of said motor to open said normally closed contacts thereby to disconnect the motor from its source and to connect said coil across said armature and field winding and to close said normally open contacts to complete a first dynamic braking circuit through said armature and field winding, a reversing type master switch and switching means controlled thereby for completing reverse power connections from said motor to said source, and means responsive to the energization of said coil only in the reverse position of said master switch for completing a second dynamic braking circuit in parallel with said armature.

10. A control system for an electric motor having an armature and a series field winding comprising in combination, limit switching mechanism actuated by said motor for disconnecting said motor from its source at a predetermined limit of operation in one direction of rotation, reversing switching means comprising a reversing type master switch and means controlled thereby for completing reverse power connections from said motor to said source to effect operation of said motor in the reverse direction, means jointly controlled by said limit switching mechanism and said reversing switching means and responsive to the voltage across said motor for completing a dynamic braking circuit in parallel with said armature, and for interrupting said dynamic braking circuit at a predetermined limit of operation of said motor in the reverse direction.

11. A control system for an electric motor having an armature and a series field winding comprising in combination, a dynamic braking resistor, limit switching mechanism for disconnecting said motor from its source at a predetermined limit of operation of said motor in one direction of rotation, completing a dynamic braking circuit through said armature, field winding and resistor, and preparing reverse power connections from said motor to said source, reversing switching means comprising a reversing type master switch and means controlled thereby for completing said reverse power connections from said motor to said source with said dynamic braking

resistor connected in parallel with said armature and field winding, and means jointly controlled by said limit switching mechanism and reversing switching means and responsive to the voltage across said motor for completing a second dynamic braking circuit in parallel with said armature only in the reverse position of said master switch, and said limit switching mechanism serving to interrupt said second dynamic braking circuit at said limit of operation in the reverse direction of rotation of said motor.

12. A control system for hoists and the like comprising in combination, an electric motor having an armature and a series field winding, an overhoist limit switch for disconnecting said motor from its source at a predetermined limit of operation in the hoisting direction and completing a dynamic braking circuit through said armature and field winding, reversing switching means comprising a master switch having a hoisting position and a lowering position and means controlled thereby for completing reverse power connections from said motor to said source to effect rotation of said motor in the reverse direction, and switching means jointly controlled by said reversing switching means and said limit switch and responsive to the voltage of said motor for completing a second dynamic braking circuit in parallel with said armature only in the lowering position of said master switch and for interrupting said second dynamic braking circuit in the lowering direction at said limit of operation.

13. A control system for hoists comprising in combination, a series hoist motor, limit switch mechanism for disconnecting said motor from its source at a predetermined limit of operation of said hoist in the hoisting direction thereby to stop said hoist within a predetermined zone, a reversing type master switch for controlling the

direction of rotation of said motor, said master switch having a plurality of speed controlling positions for the lowering direction, means responsive to progressive operation of said master switch through said positions for progressively adjusting the speed of said motor, means controlled by the operation of said limit switch for completing a dynamic braking circuit for said motor in the lowering direction and interrupting the progressive operation of said speed adjusting means within said zone and responsive to operation of said limit switch at said limit in the lowering direction for interrupting said dynamic braking circuit and restoring the progressive operation of said speed adjusting means.

14. A control system for hoists comprising in combination, a series hoist motor, limit switch mechanism for disconnecting said motor from its source at a predetermined limit of operation of said hoist in the hoisting direction thereby to stop said hoist within a predetermined zone, a reversing type master switch for controlling the direction of rotation of said motor, said master switch having a plurality of speed controlling positions for the lowering direction, a plurality of electromagnetic switching devices operable in sequence in response to progressive operation of said master switch through said speed controlling positions for progressively adjusting the speed of said motor, means controlled by the operation of said limit switch for completing a dynamic braking circuit for said motor in the lowering direction and for interrupting the sequential operation of said switching devices while said hoist is within said zone and responsive to operation of said limit switch at said limit in the lowering direction for interrupting said dynamic braking circuit and resuming the sequential operation of said contactors.

JAMES W. COOKE.
